UNITED STATES PATENT OFFICE.

EDMUND SUCKOW AND EDWARD HABEL, OF OLDSHAM, ENGLAND, ASSIGNEES TO CHARLES SUCKOW, OF BUFFALO, NEW YORK.

IMPROVEMENT IN BLOWERS.

Specification forming part of Letters Patent No. 37,325, dated January 6, 1863.

To all whom it may concern:

Be it known that we, EDMUND SUCKOW and EDWARD HABEL, of Oldham, in the county of Lancaster, England, engineers, assignors to CHARLES SUCKOW, of the city of Buffalo, county of Erie, and State of New York, United States, have invented an Improved Blower for Producing a Strong Blast or Current of Air; and we do hereby declare that the following is a full and exact description of the construction and operation thereof, reference being had to the accompanying drawings, making a part of this specification, in which—

Figure I is a longitudinal section of our improved blower. Fig. II is a plan of the screw. Fig. III is a longitudinal section of the cylinder or case, the screw being removed therefrom. Fig. IV is a plan of the cylinder or case in which the screw works.

Letters of like name and kind refer to like parts in each of the figures.

The nature of our invention relates to the arrangement of an Archimedean screw in a cylinder, which is provided with projections or catch-wings upon the inside, which lessen the friction of the screw when revolving in air, and increase the force of the current of air and prevent the return of the air; second, in surmounting the cylinder with a conical disk, forming an exhaust-chamber, through which the air is forced; third, in making the hub of the screw conical and bell-mouthed.

A represents a cylinder, within which the screw revolves. Upon the inside of this cylinder are projections or catch-wings a' , which lie at an acute angle to the screw-shaft—about forty-five degrees. These wings are of such length and so placed that they reach down from the upper part of the cylinder about one-half its length, so that about one half of the length of the blades of the screw will revolve over and close to the catch-wings while the other half of the blades expand and fill the cylinder below the catch-wings. The hub B, to which the screw-blades are attached, is made conical and hollow or bell-mouthed for about one half its length, while the other half or the apex of the cone forms a solid connection to the shaft. The blades C of the screw are placed and securely fastened upon the hub and in a contrary direction to the catch-wings,

so that when the screw is put into the cylinder the blades will revolve crosswise of the catch-wings. There are secondary blades put upon the hub between the blades C, which are shorter than the blades C. These are represented at D. That part of the blades which pass over the catch-wings are cut out in a manner to allow them to pass over the catch-wings in the closest possible proximity thereto, while the part below the wings expands to the full diameter of the cylinder. A conical disk, E, surmounts the cylinder, which forms a capacious exhaust-chamber in front of the screw, through which the air or water or other fluid is discharged. The discharging-spout or conducting spout or hose is connected in a suitable and convenient manner to the flange or top of this chamber at E^2 . Cross-bars are also placed in this chamber, as shown at F, for supporting the upper end of the screw-shaft, a suitable journal-bearing being formed at the junction of these arms for that purpose. These bars have their surfaces at an angle corresponding to the angle of the catch-wings.

G is a standard or support for the lower end of the screw-shaft. This projects from a plate, H, which plate has a permanent connection to the cylinder. A suitable journal-bearing is placed in this standard, as shown at G^2 . At the lower end of the cylinder, at which the air or fluids enter, there is secured a plate or ring, I. This ring is for the purpose of lessening the opening and preventing a backdraft of air or return of fluid. A suction pipe or hose is connected to this ring when the apparatus is used for forcing water or other liquids.

L represents a tube for conveying oil to the upper journal. m is a passage way or tube for conveying oil to the lower journal.

A driving-pulley is placed upon the screw-shaft, as shown at J.

The bell-mouth of the screw-hub opens into, enlarges, and adds to the effectiveness of the exhaust-chamber.

The screw, and consequently the cylinder in which it works, may be of any desired diameter and length, and the machine may be worked with equal effect in a vertical, horizontal, or angular position.

This invention is not only applicable for producing a strong blast or current of air, but is also designed for and applicable to machin-

ery or apparatus used for opening or cleaning fibrous materials, such as cotton-openers, cotton-gins, and the like. It is also designed for and applicable for compressing air or gas, and for lifting and forcing water and other fluids. It forms one of the most effective force-pumps in use.

What we claim as our invention, and desire to secure by Letters Patent, is—

1. The arrangement and combination of an Archimedean screw with a cylinder having catch-wings a' upon the inside thereof, for the purposes and substantially as described.

2. Placing and using the blades of an Archimedean screw upon a conical and bell-mouthed hub, for the purposes and substantially as set forth.

3. The combination of the conical disk E with the cylinder A and Archimedean screw, for the purposes and substantially as set forth.

ENMUND SUCKOW.
EDWARD HABEL.
